UNITED STATES PATENT OFFICE.

HARLON FINLEY ONG, OF WENDLING, OREGON.

AIR-BRAKE ATTACHMENT.

SPECIFICATION forming part of Letters Patent No. 743,916, dated November 10, 1903.

Application filed September 23, 1902. Serial No. 124,513. (No model.)

To all whom it may concern:

Be it known that I, HARLON FINLEY ONG, a citizen of the United States, and a resident of Wendling, in the county of Lane and State of Oregon, have invented a new and Improved Air-Brake Attachment, of which the following is a full, clear, and exact description.

In the use of air-brake systems as now generally organized when a train is left standing with the brakes applied the gradual leakage of the air will ultimately result in the release of the brakes, and the train is therefore liable to be accidentally moved. This condition is particularly dangerous when trains are left standing on grades. The purpose of this invention is to provide a means acting as an auxiliary to the ordinary brake apparatus and serving automatically to apply the brakes should the car or train of cars begin to move and also acting automatically to release the brakes upon the proper action of the engineer or other trainman upon the ordinary brake apparatus.

To this end the invention comprises, specifically stated, a reservoir having communication with the train-pipe, a valve controlling such communication, a means operated from a mobile part of the car or train of cars for operating the valve upon the movement of the car or train, and a motor controlled by the train-pipe pressure, by which motor the said valve-operating means is thrown into and out of action. When the train-pipe pressure is lowered, the motor permits the movement of the valve-operating means into active position, and then should the brakes become released the least movement of the train will drive the valve-operating means to open the valve and allow the pressure from the said reservoir to pass into the train-pipe, thus setting the triple valve to release position. The continued operation of the motor, in conjunction with the movement of the valve-operating means, then throws the valve to exhaust position and exhausts the train-pipe pressure whereby again to apply the brakes. After the train-pipe pressure is reduced and the brakes are again applied the reduced pressure in the motor allows the valve-operating means to move again into operative position, so as to be ready for a repetition of the above-described operation should the brakes again

become released. When the train-pipe pressure is increased from the main reservoir of the usual brake apparatus, this increased pressure operates the motor so as to hold the valve-operating devices in inactive position, and thus my improved attachment is arranged not to affect the ordinary operation of the brake apparatus from the engineer's cab.

This specification is an exact description of one example of my invention, while the claims define the actual scope thereof.

Reference is to be had to the accompanying drawings, forming a part of this specification, in which similar characters of reference indicate corresponding parts in all the views.

Figure 1 is an elevational view showing the apparatus in use. Fig. 2 is a detail section on the line 2 2 of Fig. 1. Fig. 3 is an enlarged sectional view on the line 3 3 of Fig. 4, showing the motor and the valve-operating means. Fig. 4 is a sectional plan view on the line 4 4 of Fig. 3. Figs. 5, 6, and 7 are diagrammatic views illustrating the successive positions of the valve with respect to the stationary cam which controls the action of the valve-operating means, and Fig. 8 is a diagram showing the relation of my invention to the conventional brake system.

In Fig. 8, P indicates the air-pump, E the engineer's brake-valve, D the main drum, 10 the train-line, C the brake-cylinder, A the auxiliary and V a triple valve, of the conventional fluid-pressure brake system.

The apparatus is preferably applied to the posterior end of the train. In Figs. 1 and 8 I have shown it fitted to the caboose-car, which is generally coupled to the end of a freight-train. In this view 10 indicates the train-pipe, and it should be assumed that this is arranged with the other parts of the ordinary brake system in the usual or any known manner. 11 indicates a branch pipe which passes from the train-pipe up to the valve 12 and to a pipe 14, running from the reservoir 15 to the pipe 11. 16 indicates a pipe which passes by the valve 12 and leads from the end of the pipe 14 to the pipe 11 at a point intermediate the valve 12 and the pipe 10. 17 (see Figs. 1 and 3) indicates a pressure-relief device placed in communication with the pipe 11 and serving to allow the gradual leakage of pressure from this pipe, but preventing a

sudden reduction of pressure. This pressure-relief device comprises a shell and a loose plate 17^a, which allows a low pressure to pass it, but which is lifted by a strong pressure 5 and closes the shell, thus preventing the escape of such pressure. 18 (see Figs. 1 and 2) indicates a check-valve in the pipe 16, said valve opening toward the reservoir 15. To charge the reservoir 15, pressure is admitted 10 to the train-pipe, and it passes then to the pipe 11, where it is stopped by the valve 12. The pressure device 17 closes upon the sudden increase of pressure, thus preventing the escape of this pressure. The train-pipe 15 pressure therefore passes through the pipe 16, past the valve 18, and into the reservoir 15. This pressure is at all times retained 20 by the valve 18 and normally by the valve 12.

In Figs. 5, 6, and 7 the pipes 10 and 11 and 25 the reservoir 15 are indicated diagrammatically. The valve 12 comprises a casing or body having ports 19, communicating with the pipe 11, and a port 20, communicating with the atmosphere. In the valve-casing 30 12 a plug 21 operates, and this plug has a passage 22, which when the plug is properly positioned serves to open the pipe 11. (See Fig. 6.) The plug also has a passage 23, which when the plug is properly positioned 35 places the train-pipe 10 in communication with the atmosphere. (See Fig. 7.) This plug 21 is also capable of movement to close all of the ports 19 and 20. (See Fig. 5.)

The motor as here shown comprises a stationary cylinder 24, with a piston 25 movable 35 therein. A relatively small pipe 26 leads from the pipe 11 on the train-pipe side of the valve 12 into the cylinder 24, this pipe feeding the cylinder 24, and thus causing the piston 25 to move upward. A rod 27 is connected to the piston and passes out at the top of the cylinder, the upper end of the rod being joined to a cross-head 28, in turn connected with side rods 29, which pass down 40 through suitable guides 30 and carry at their lower ends below the cylinder 24 a cross-head 31.

32 indicates a stem attached to the plug 21 of the valve 12, this stem being of flat or 45 other angular cross-sectional form and fitted to slide but not to turn within a tube 33. Said tube is mounted to turn in and to move with the cross-head 31 and carries at its upper end a disk-like head 34, whereto is attached a pin 35. This pin plays in a cam-grooved plate 36, fastened rigidly alongside of the cross-head parallel to the path of vertical movement thereof, as best shown in Figs. 1 and 4. Said plate 36 has formed therein a 50 groove comprising a horizontal transverse run 37, at the right-hand end of which is a vertically-disposed run 38, leading to an upwardly and leftwardly inclined run 39. This run 39 terminates in a downwardly and leftwardly 55 inclined run 40, leading into a vertical run 41 at the left-hand side of the plate at a point intermediate the ends of said run 38. This

run 41 leads from the left-hand end of the run 37 to the top of the plate. Fastened in the lower end of the tube 33 is a rod 42, which projects down through the floor of the car and carries (see Figs. 1 and 2) a pivoted arm 43, held in active position by a spring 44. This arm 43 carries a pin 45, which is engaged by a cam 46, fastened to the axle 47 or to some other part swinging revolubly in unison with the movement of the car. This cam is so disposed that upon the movement of the train involving a slight rotary movement of the axle 47 the shaft 42 will, through the medium 80 of the arm 43, be rocked to move the disk 34, so that the pin 35 is thrown from the left-hand end of the run 37, which is its position of rest, (see Fig. 5,) to the right-hand end of said run, (see Fig. 6,) thus moving the plug 85 21 of the valve 12 from the closed position (shown in Fig. 5) to the position shown in Fig. 6, in which the pipe 11 is open throughout its length and the train-pipe is placed in communication with the reservoir 15.

When the train-pipe pressure is high and the brakes are released, this pressure will keep the piston 25 raised and through the medium of the parts 27, 28, 29, 31, and 33 the rod 42 will be raised clear of the cam 46. 95 After the train-pipe pressure is reduced to apply the brakes the piston 25 gradually descends, owing to the escape of the pressure through the tube 26 and past the retaining device 17, and thus the shaft 42 is again lowered, so that the pin 45 reengages the cam 46. The parts stay in this position, and should the leakage from the brake-cylinder result in a release of the brakes and the train begin to move the cam 46 will act on the 105 shaft 42 and throw the collar 34, so that the pin 35 is moved from the position shown in Fig. 5 to that shown in Fig. 6, thus moving the plug-valve 21, so as to open communication between the reservoir 15 and the train-pipe 10. The superior pressure with which this reservoir had been previously charged will then fill the train-pipe and throw the triple valve into release position. This increase of pressure in the train-pipe, and consequently in the pipe 11, will cause such pressure to be communicated through the pipe 26 to the cylinder 24, and the piston 25 will be raised. This movement of the piston 25 carries with it the cross-head 31 and pin 35, and 110 said pin rides up the run 38 of the groove in the plate 36 and thence through the inclined run 39, causing the pin 35 to assume the position shown in Fig. 7 and resulting in a corresponding movement of the valve-plug 21, 115 so as to place the train-pipe 10 in communication with the exhaust-port 20 of the valve 12. This exhausts the train-pipe pressure and again applies the brakes. As the train-pipe pressure is exhausted and the pressure 120 of the cylinder 24 leaks out through the pressure device 17 the piston 25 again drops to its lower position and the pin 35 moves through the inclined run 40 of the cam-groove and 125 130 135

down through the lower portion of the vertical run 41, thereby returning to the position of rest, (shown in Fig. 5,) the parts again assuming the position indicated in Fig. 1, in which position they are ready for a repetition of the above-described operation. As long as the brakes are applied and no movement of the cam 46 takes place the pin 35 lies as shown in Fig. 5, and then when the engineer varies the train-pipe pressure in the ordinary operation of the brake system the pin 35, with the parts in connection therewith, merely move vertically without any turning movement. It is for this purpose that the run 41 in the slot of the cam-plate 36 is provided, by which run this non-operative vertical movement of the pin 35 is allowed.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. The combination with an air-brake system, of a reservoir, a pipe leading therefrom, two branch pipes communicating with the first-named pipe and with the train-pipe, a check-valve in one of said branch pipes, a valve in the other branch pipe, for the purpose specified, and means for operating the valve, such means comprising a part in connection with a mobile part of the vehicle to which the brake is applied.

2. The combination with an air-brake system, of a pressure-reservoir for the purpose specified, means controlling the communication of said reservoir with the brake system, an operating device for said means, the operating device including a member driven from a mobile part of the vehicle to which the brake is applied, and an automatically-operated motor for moving the operating device into and out of active position.

3. The combination with an air-brake system, of means controlling the application of the brakes, an operating device therefor, said device including a member driven from a mobile part of the vehicle to which the brake is applied, and a fluid-operated motor communicating with the brake system and connected with the said operating device to move it automatically into or out of active position.

4. In a fluid-pressure brake system, the combination of a pressure-reservoir for the purpose specified, a valve controlling the communication of said reservoir with the brake system, an operating device for the valve, the operating device being driven from a mobile part of the vehicle to which the brake is applied, and means for automatically moving the operating device into and out of active position.

5. In a fluid-pressure brake apparatus, the combination of a valve, a shaft having slid-

ing connection therewith, means for imparting a turning movement to the shaft to operate the valve, and means for automatically sliding the shaft to engage or disengage said means for imparting a turning movement thereto.

6. In a fluid-pressure brake apparatus, the combination of a valve, a shaft having sliding connection therewith, means for imparting a turning movement to the shaft, a stationary cam with which the shaft coacts to impart a further turning movement thereto, and means for sliding the shaft.

7. In a fluid-pressure brake apparatus, the combination of a valve, a shaft having sliding connection therewith, means for sliding the shaft, and a stationary cam with which the shaft coacts, whereby to turn the shaft upon the sliding thereof.

8. In a fluid-pressure brake apparatus, the combination of a valve adapted to be moved to a plurality of positions, a member having sliding connection with the valve, means for turning said member to move the valve to one position, means for sliding said member, and a stationary cam with which the said sliding member coacts, whereby to turn the valve in a second position.

9. In a fluid-pressure brake apparatus, the combination of a valve, a member having sliding connection therewith, means for turning the member, means for sliding said member toward and from the means for turning it, and a stationary cam-grooved plate with which a part on the said sliding member coacts, whereby to turn the sliding member upon the sliding movement thereof.

10. The combination with a fluid-pressure brake system including a train-pipe, brake-valve, main drum, auxiliary reservoir, brake-cylinder and triple valve of an auxiliary apparatus for reapplying the brakes, said auxiliary apparatus including a pressure-reservoir separate from the main drum and auxiliary reservoir, and means controlling the communication of said reservoir with the brake system.

11. The combination with a fluid-pressure brake system including a train-pipe, brake-valve, main drum, auxiliary reservoir, brake-cylinder and triple valve, of an auxiliary apparatus for reapplying the brakes, said auxiliary apparatus including a pressure-reservoir separate from the main drum and auxiliary reservoir, means controlling the communication of said reservoir with the brake system, and means for automatically operating said controlling means.

12. The combination with a fluid-pressure brake system, of an auxiliary apparatus for reapplying the brakes, said auxiliary apparatus including a pressure-reservoir, and means controlling the communication of said reservoir with the train-pipe, and also controlling the communication of the train-pipe with the atmosphere.

13. The combination with a fluid-pressure brake system, of an auxiliary apparatus for

- reapplying the brakes, said auxiliary apparatus including a pressure-reservoir, means controlling the communication of said reservoir with the train-pipe and also controlling the communication of the train-pipe with the atmosphere, and an automatic operating device for said means.
- 14.. The combination with a fluid-pressure brake system, including the train-pipe, brake-valve, main drum, auxiliary reservoir, brake-cylinder and triple valve, of an auxiliary apparatus for reapplying the brakes, said apparatus comprising a pressure-reservoir separate from the main drum and auxiliary reservoir, means for controlling the communication of said pressure-reservoir with the brake system, and automatic operating devices for said controlling means, the operating devices comprising a part capable of connection with a mobile part of the vehicle to which the brake is applied, whereby to start the action of said operating devices upon the movement of the vehicle.
15. The combination with a fluid-pressure brake system, of an auxiliary apparatus separate from the brake system and capable of reapplying the brakes, and means for automatically operating said auxiliary apparatus, such means including a part capable of connection with the mobile part of the vehicle to which the brake is applied, whereby to start the action of said operating means upon the movement of the train.
16. The combination with a fluid-pressure brake system, of an auxiliary apparatus separate from the brake system and capable of reapplying the brakes, means for automatically operating said auxiliary apparatus, such means including a part capable of connection with the mobile part of the vehicle to which the brake is applied, whereby to start the action of said operating means upon the movement of the train, and devices controlled by the train-pipe pressure, for moving said part in and out of connection with said mobile part of the vehicle.
17. The combination with a fluid-pressure brake system, including the train-pipe, brake-valve, main drum, auxiliary reservoir, brake-cylinder and triple valve, of an auxiliary apparatus for reapplying the brakes, said apparatus comprising a pressure-reservoir separate from the main drum and auxiliary reservoir, means for controlling the communication of said pressure-reservoir with the brake system, automatic operating devices for said controlling means, the operating devices comprising a part capable of connection with a mobile part of the vehicle to which the brake is applied, whereby to start the action of said operating devices upon the movement of the vehicle, and devices controlled

by the train-pipe pressure for moving said part in and out of connection with said mobile part of the vehicle.

65

18. The combination with a fluid-pressure brake system, of an auxiliary apparatus separate from the brake system and capable of reapplying the brakes, said apparatus comprising a pressure-reservoir, a valve controlling its communication with the train-pipe and the communication of the train-pipe with the atmosphere, two devices for jointly operating the valve, the one of said devices being capable of connection with a mobile part of the vehicle to which the brake is applied, and means controlled by the train-pipe pressure for moving the first named of said valve-operating devices in and out of connection with said mobile part of the vehicle and for actuating the other valve-operating device.

70

75

19. The combination with a fluid-pressure brake system, of an auxiliary apparatus separate from the brake system and capable of reapplying the brakes, said apparatus comprising a pressure-reservoir, a valve controlling its communication with the train-pipe and the communication of the train-pipe with the atmosphere, two devices for jointly operating the valve, the one of said devices being
